UNITED STATES PATENT OFFICE.

PETER M. KNUDSEN, OF NEW YORK, N. Y.

SKYLIGHT.

Application filed June 28, 1921. Serial No. 480,989.

To all whom it may concern:

Be it known that I, PETER M. KNUDSEN, a citizen of the United States, residing at New York, in the county of Bronx and State of New York, have invented certain new and useful Improvements in Skylights, of which the following is a full, clear, and exact specification.

This invention relates to skylights, and has for its object to provide an improved and simplified construction wherein the glass is supported securely in proper position, leakage is prevented and provision is made for ventilating the building through the skylight.

A special object is to provide a gutter of improved construction which permits the external discharge of any water that penetrates the skylight and also serves as a means for supporting the glass. Another special object is to simplify and improve the construction of the ribs which support and cover the lateral edges of the glass. The invention will be further hereinafter described in connection with the accompanying drawings which constitute part of this specification, and then more specifically defined in the claims at the end of the description.

In the accompanying drawings, wherein similar reference characters are used to designate corresponding parts throughout the several views:

Figure 1 is a plan view of a skylight constructed substantially in accordance with this invention.

Figure 2 is a section taken on the line II—II of Figure 1.

Figure 3 is a side elevation of the gutter drawn to a larger scale and showing more clearly the manner of connecting the ribs thereto.

Figure 4 is a section on the line IV—IV of Figure 2, also drawn to a larger scale.

Figure 5 is a section on a larger scale taken along the line V—V of Figure 2.

Figures 6 and 7 are side and plan views respectively of the lower member of the rib illustrated in Figures 1 to 5, inclusive.

Figures 8 and 9 are similar views of the upper member of said rib.

Figure 10 is a detailed sectional view of the gutter.

Figure 11 is a detailed view of a modified

form of lower member of the rib, showing how two of said members of opposite ribs may be made in one piece, and

Figures 12 and 13 are detailed sectional views of modified forms of ribs, these sections corresponding to that shown in Figure 4.

In Figure 2, 5 indicates a frame such as is constructed on the roof of a building for supporting a skylight and around which is fitted the metal flashings 50. Above said flashings and also fitted to the outside of the frame 5 are gutters 23 consisting of sheet metal strips bent to the form illustrated in Figures 2 and 10, each gutter having an inclined outer member 3 which extends upward a distance sufficient for supporting the glass 4 and the ribs 2. At the lower edges of the portions 3 of the gutters there are formed troughs 24 having perforations 25 in their bottoms for the discharge of any water that may collect therein.

Said ribs 2 extend at right angles to the portions 3 of the gutters and rise to the ridge of the skylight where their upper ends are covered by an arch-shaped ridge member 1.

As illustrated in Figures 1 to 9, inclusive, each rib 2 consists of a lower member 11 for supporting the lateral edges of the glass 4, and an upper member 12 for covering the same. Both members 11 and 12 have outwardly turned flanges 14 to engage the upper and lower faces of the glass, as best shown in Figure 4. Said members 11 and 12 are preferably made in channel form and together make up ribs which are generally tubular in shape, being connected together by bolts 13 which also serve to clamp the margins of the glass firmly between the flanges 14. The upper ends of the members 11 of aligned ribs on opposite slopes of the skylight may be connected by bowed straps 17, Figure 2, which may be riveted to said members, as at 18. These straps 17 are connected to the ridge member 1 by bolts 8 which serve to hold the latter firmly down in place with its lateral flanges 10 engaging the upper faces of the plates of glass 4.

Below the ridge member 1 there is arranged a trough-shaped member 7 having its marginal portions bent to form grooves 9 to fit over the upper ends of the plates of glass 4. Below the grooves 9 the marginal portions of the trough-shaped member 7 are

doubled upon themselves, as at 16, to form supports for the glass. The upper ends of the lower members 11 of the ribs 2 extend through the sides of the trough-shaped member 7, as shown in Fig. 2, just below the doubled portions 16.

As shown in Figs. 2, 6 and 7, the lower member 11 of each rib is formed with a notch 27 to permit water which enters the rib 10 to escape to the trough 24. Tongues 15 are formed at the outer ends of the flanges 14 on the member 11 for connecting the same to the portion 3 of the gutter. The upper end of the member 11 is notched out at 160 to fit the rounded edges of the doubled portions 16 of the trough-shaped member 7. The upper member 12 of each rib has tongues at its lower end to engage with upward projections 26 on the portion 3 of the gutters, as 15 best shown in Fig. 3. The upper ends of said members 12 are curved to conform to the arched sides of the member 1, as shown in Figures 8 and 9, and are also provided with tongues 20 which interlock with said member 1, as illustrated in Figures 2 and 5. The upper end portion of the member 12 is notched at 21 on each side to fit over the flanges 10 on the member 1.

The member 7 has a slot 28 formed therein, and the ridge member 1 has an opening 280 at one end thereof leading to a ventilator 29, see Figs. 1 and 2, so that air may escape from the interior of the building through the skylight. It will be understood that all the points between metal parts of the skylight should be soldered to make them water tight. For instance, the upper ends of the upper members 12 of the ribs should be soldered to the sides of the ridge member 1, and the lower ends of said members 12 soldered to the projecting portions 26 on the parts 3 of the gutters. Should leaks occur at these or other points, the water which enters the ribs will find an outlet through the openings 27 and troughs 24 without coming into the building.

As shown in Fig. 11, the lower members 11 of the ribs which are arranged in alignment with each other on opposite slopes of the skylight may be made in one piece, having an arched connecting portion 170. In this formation the bolts 8 are passed through the connecting portion 170 in the same manner as they are engaged with the straps 17 in Fig. 2.

The formation of the upper and lower members of the ribs 2 may be modified as suggested in Figs. 12 and 13. In the first of these figures, the lower member 110 of the rib is made substantially as shown in Fig. 4 with flanges 140 for supporting the glass 4, but the upper member 120 has its marginal portions rebent upon themselves at 142 and their extremities turned down at 144 to engage the lateral edges of the glass.

The members 110 and 120 are connected together by bolts 130 corresponding to the bolts 13 in Figs. 1 to 4 inclusive.

In Fig. 13 the lower member 111 of the rib is made substantially as shown in Figs. 4 and 12 but the marginal flanges 112 thereof do not contact with the glass 4 because in this form of rib a cover 36 is provided for said member 111 which has grooved marginal portions 38 engaging the flanges 112 and themselves supporting the glass. The cover 36 has its middle portion raised or offset at 37 to engage the ends of the glass, and bolts 131 are passed through said raised portion 37 for connecting the lower member 111 to the upper member 121 of the rib. Said upper member 121 is formed substantially as shown in Fig. 4 with marginal flanges 141 engaging the upper surface of the glass. The opening or slot 39 in the member 111, Figure 13, corresponds to the notch 27 in the member 11, Figures 2 and 7, for emptying any water which may accumulate in the rib into the trough or the gutter.

I claim:

1. In a skylight, the combination with marginal gutters having upwardly projecting flanges at their outer edges, of lower rib members supported on said gutters and having their outer ends abutting against said flanges, plates of glass mounted on said lower rib members and also abutting against said flanges, an arched ridge member covering the upper ends of the glass plates and connected to the rib members, upper rib members covering the lateral edges of the glass plates and extending from the flanges on the gutters to said ridge member, and a trough-shaped member arranged below the ridge member and having marginal grooves engaging the upper ends of the glass plates, said lower rib members extending through said trough-shaped member for connection with the ridge member.

2. In a skylight, the combination with marginal gutters having upwardly projecting flanges at their outer edges, of lower rib members supported on said gutters and having their outer ends abutting against said flanges, plates of glass mounted on said lower rib members and also abutting against said flanges, an arched ridge member covering the upper ends of the glass plates and connected to the rib members, upper rib members covering the lateral edges of the glass plates and extending from the flanges on the gutters to said ridge member, and a trough-shaped member arranged below the ridge member and having marginal grooves engaging the upper ends of the glass plates, said lower rib members extending through said trough-shaped member for connection with the ridge member and conforming to the lower edges of the glass-en-

gaging grooves of said trough-shaped member.

3. In a skylight, the combination with marginal gutters having upwardly projecting flanges at their outer edges, of lower rib members supported on said gutters and having their outer ends abutting against said flanges, plates of glass mounted on said lower rib members and also abutting 10 against said flanges, an arched ridge member covering the upper ends of the glass plates and connected to the rib members, upper rib members covering the lateral edges of the glass plates and extending from 15 the flanges on the gutters to said ridge member, a trough-shaped member arranged below the ridge member and having marginal grooves engaging the upper ends of the glass plates, said lower rib members extending 20 through said trough-shaped member for connection with the ridge member, there being an air passage in the base of said trough-shaped member, and a ventilator at one end of the ridge member for the purpose specified.

4. In a skylight, the combination with marginal gutters having upwardly extending flanges at their outer edges, of lower rib members supported on said gutters and 30 abutting at their outer ends against said flanges, said rib members extending upwardly from opposite gutters to form a ridge, glass plates mounted on said lower rib members and also abutting against the 35 flanges on the gutters, an arched ridge member covering the upper ends of the glass plates, upper rib members covering the lateral edges of the glass plates and extending from the flanges on the gutters to

said ridge member, bowed straps connecting the upper ends of adjacent lower rib members on opposite slopes of the ridge, and means of connection between said straps and the ridge member.

5. In a skylight, the combination with marginal gutters having upwardly extending flanges at their outer edges and lower drip openings, of lower rib members supported on said gutters and having their outer ends abutting against said flanges, plates of glass mounted on said lower rib members and also abutting against said flanges, an arched ridge member covering the upper ends of the glass plates and connected to the rib members, and means for connecting and supporting the upper marginal ends of said glass plates consisting of a trough-shaped member having marginal grooves engaging said glass plates, and ventilator openings.

6. In a skylight, the combination with marginal gutters having drip openings and upwardly extending flanges at their outer edges, of lower rib members supported on said gutters and having their outer ends abutting against said flanges, plates of glass, mounted on said lower rib members and also abutting against said flanges, an arched ridge member, and means for ventilating the same, and a trough-shaped member arranged below the ridge member and having ventilator openings and marginal grooves, said grooves engaging the upper ends of the glass plates.

In testimony whereof I have signed my name to this specification.

PETER M. KNUDSEN.
